METHOD OF PROMOTING COMBUSTION.

987,316.

Specification of Letters Patent. Patented Mar. 21, 1911.

Application filed April 19, 1910, Serial No. 556,426. Renewed October 26, 1910. Serial No. 589,262.

To all whom it may concern:

Be it known that I, JOHN H. PARSONS, a citizen of the United States, residing at Ridley Park, in the county of Delaware and State of Pennsylvania, have invented certain new and useful Improvements in Methods of Promoting Combustion, of which the following is a specification, reference being had therein to the accompanying drawing.

This invention relates to a method of promoting combustion of fuel, such as coal, in boiler furnaces, although in that particular, the method may be carried out in connection with other types of furnaces or heaters.

It is, at the present time, a well known fact that in operating under the general practice it is necessary to create in furnaces the chemical combination of the combustible gases with oxygen. This combination is known technically as "combustion." It is also a recognized fact that to maintain this combustion it is necessary to create a circulation of air through the combustible body of fuel on the grate, and this has been secured, either by increasing the pressure from below the grate or decreasing the pressure above the grate, so that the pressure below will result in the forcing of the air through the ignited body of fuel.

It is a fact known in this particular art that heretofore, or prior to my invention, it was quite impossible to supply a sufficient amount of oxygen for a complete combustion of the combustible gases arising from the burning bed of fuel when such oxygen or air was supplied through the fuel and grate bars. Realizing this fact, many inventors of the past have suggested apparatus for introducing air above the burning bed of fuel into the fire box. This air was intended to supply oxygen for effecting combustion of these combustible gases prior to their entry into the uptake.

Appreciating the efforts heretofore made, and the objections to the general practice as adopted prior to my invention, I have ascertained that to secure substantially complete combustion, the bed of fuel should be maintained largely as a gas-producing element, and the distilled gases arising therefrom employed as the combustible material with which to produce the requisite heat for the boiler. In this connection, the maintenance of the fire on the grate in a proper

condition for distillation has been ascertained by me to be a factor of material importance and I have ascertained that the burning body of fuel should be under control so that according to requirements, the distillation may be varied as to rapidity so that the combustible fuel relied on for steaming purposes will be constantly supplied in the proper amounts according to the requirements of the conditions encountered. In locomotive practice, it is realized that the steaming conditions are variable according to the load and grade, and therefore when additional steam is required, the heat producing factor or element should be changed or amplified in accordance with the increased requirements.

I have ascertained that it is quite impossible, as above stated, to supply all of the air through the burning bed of fuel, and therefore in my method presently to be described, I supply the oxygen above the burning bed of fuel and in such manner as will tend to regulate the amount of oxygen supplied through the bed of fuel so that the distillation of the gases may be regulated according to the requirements of the conditions met with. I have found that the amount of oxygen to be introduced above the bed of fuel should be in very large quantities and should be directed under considerable force so that an entraining action of the air through the fuel will be secured.

Briefly, my method may be stated as follows: I supply the proper amount of fuel on the grate and ignite the same, the air being supplied at the initial stage in any convenient manner, or as usual. I then inject into the rising gases distilled from the burning bed of fuel, a very large volume of air which has been previously heated. This air is directed forward in the general direction of the draft of the furnace preferably toward the lowermost exhaust flue thereof as indicated in Fig. 1 and with such force as to produce an entraining action of air through the burning bed of fuel. The greater the force the greater will be the rapidity and consequently the amount of air passing through the fuel will be greater and therefore the more rapid the distillation of the gases therein contained. These gases in their highest degree of temperature rise from the burning bed of fuel in the fire box, are met by the incoming heated air and

commingle therewith, thus creating combustion and maintaining the conditions of the combustible gases in substantially their most perfect condition, namely CO_2 without permitting them to be reconverted into the less perfect condition of CO . The impelling force for the heated air is considerable and the term "force" is employed herein as indicating that rapidity of movement which will create a drawing or entraining action of the air allowed to pass through the bed of fuel. This is to distinguish that feature of the method from the suggestions heretofore made by others of simply permitting air to enter with inconsiderable force. This latter suggestion stifled the draft and impeded the action of the furnace. I have also ascertained that by introducing the air into the combustion chamber above the bed of fuel under this entraining force, the air should be supplied in such volume or quantity as to complete the combustion of the combustible gases and suspended carbon and to cover the entire area of the furnace. I have also ascertained that in practice the method above described can only be carried out satisfactorily by directing the entraining volume in the general direction of the draft so that the incoming air will assist the draft rather than impede the same and serve in the capacity of an entraining factor as above described.

Any convenient form of apparatus may be employed so long as the proportions are properly such as to permit the requisite volume of air to be injected or forced into the fire box and with sufficient speed or momentum as to produce the required result above stated. I have shown, for convenience, somewhat diagrammatically, an apparatus for this purpose.

In the drawings: Figure 1 is a longitudinal vertical section through a locomotive boiler, Fig. 2 is a sectional plan.

A indicates the flue sheet, B the grate bars, C the ash pit which is open at D, the opening being sufficient to supply the maximum amount of air to the grate bars. The door is indicated at E and the boiler at F.

Any preferred form of furnace can be employed, but the above form is illustrated for the purposes of this specification only.

Located conveniently at opposite sides of the fire box are what I have termed heater boxes or stoves G the ends adjacent the door being supplied with upwardly extending conductor sections H capped with suitable nozzles J. These nozzles are arranged so that the incoming air will be directed in the general direction of the draft and toward the lowermost exhaust flues. The air supply to the heater box is at G' through the ash-pit at the rear end, and a series of baffles, such as g are interposed in the box G. To create the necessary impelling or entraining

movement of the air from the nozzle, a supply pipe K is provided with an injector point k. This supply pipe may lead from a blower or from the steam dome as may be required and is governed by a valve L. In 70 constructing the nozzles they are conveniently so arranged in proportion that the air will be substantially in sheet form and the size of the outlet ends of the nozzle is such as to permit a very large volume of air to be 75 introduced into the fire box and so under necessary force for the purpose stated.

I have not herein claimed the specific form of apparatus, but in that particular would state that the invention is not limited to the 80 particular apparatus shown but can be carried out as a method with apparatus differing materially from that shown and described.

In operation, with a view of carrying out 85 the method, the air passing through the heater box or pipes and nozzles is projected forcibly (in this connection in some instances as high as 4500 feet per minute) forwardly in the general direction of the draft. The 90 entraining volume of air is heated as it passes through the burning bed of fuel in that the supply conduits pass through the burning bed of fuel. I have found that the air will be heated by this means to a temperature sufficient to cause an immediate 95 combustion of the gases without any detrimental or objectional impeding of the combustion. Should more or less air be required, the same may be supplied in the 100 proper quantities by the control of the valve governing the steam inlet. In locomotive practice, the air passing into the intakes will vary according to the speed of the engine, but may be governed in any convenient 105 manner, as by suitable valve mechanism.

By my method the furnace condition is maintained in its most effective state, the combustible gases are consumed and the engine, if the apparatus is employed on a locomotive or the stack in stationary plants, is rendered substantially smokeless. I have also found that the steaming qualities of the engine or furnace is improved in a large degree and that the walls of the fire box and the tubes of a tubular boiler are maintained 110 practically in a white condition, indicating 115 complete combustion of the combustible gases.

Having thus described my invention, what 120 I claim is:—

1. The art of promoting combustion in furnaces consisting in igniting a body of fuel supported on a grate, supplying air below the ignited body of fuel, introducing 125 above said body of fuel heated air in the general direction of the draft of the furnace and in such volume as to oxidize the combustible gases and consume the carbon particles arising from the body of fuel, the vol- 130

ume and velocity of the introduced air being such as to cause an entraining action on the air passing through the bed of fuel whereby the amount of air passing through the bed of fuel is regulated by the regulation of the volume and velocity of the air introduced above the fuel.

2. The art of promoting combustion in furnaces consisting in igniting a body of fuel supported on a grate, supplying air to the fuel from below the grate, and forcibly introducing above the fuel a volume of heated air in the general direction of the draft of the furnace and in sheet formation to intercept and in volume to insure the consumption of the combustible gases and particles arising from the body of fuel, the volume and velocity of the introduced air being such as to cause an entraining action on the air passing through the grate and fuel and facilitate the maintenance of the required draft through the fuel.

3. The art of promoting combustion in

furnaces provided with suitable exhaust flues for the escaping products of combustion, consisting in igniting a body of fuel supported on a grate, supplying air to the fuel from below the grate, and forcibly introducing above the fuel a volume of heated air in the general direction of the draft of the furnace and substantially in line with the lowermost exhaust flue thereof and in sheet formation to intercept and in volume to insure the consumption of the combustible gases and particles arising from the bed of fuel, the volume and velocity of the introduced air being such as to cause an entraining action on the air passing through the grate and fuel and facilitate the maintenance of the required draft through the fuel.

In testimony whereof I affix my signature in presence of two witnesses.

JOHN H. PARSONS.
